SORTING MACHINE

Eugene A. Ford, Scarsdale, N. Y., assignor, by
mesne assignments, to International Business
Machines Corporation, New York, N. Y., a cor-
poration of New York

Application November 1, 1930, Serial No. 492,644

8 Claims. (Cl. 209—110)

This invention relates to machines adapted to sort perforated record cards such as disclosed in my pending application No. 348,395 filed March 20, 1929 for Improvements in sorting machines for record cards.

In these machines, cards are placed in the machine in a single stack and are fed from the stack one by one and distributed into separate pockets according to the data contained in the particular column being analyzed. The speed at which such machines operate is governed by the time required to translate the reading taken from the card into terms of a definite pocket and to operate the sorting mechanism to cause the card to be delivered to such pocket; the speed at which the cards may be fed is otherwise practically unlimited.

One of the objects of the present invention is to devise means for quickly operating the card sorting mechanism after the card has been analyzed.

Another object is to devise the sorting mechanism in which several electromagnets are employed to control the operation of the card sorting mechanism.

Another object is to provide an electromagnetic control latching device in which one electromagnet serves to release a latch which is adapted to then be actuated by spring pressure and in which a separate electromagnet is adapted to also act directly upon the latching device to hasten its operation.

Referring to the drawings wherein I have shown what I now consider to be a preferred form of my invention.

Fig. 1 is a perspective view of a sorting machine embodying my invention;

Fig. 2 is a view partly in section of the analyzing and controlling portion of the machine;

Fig. 3 is a detail plan view of the electromagnets and mechanism controlled thereby for determining the destination;

Fig. 4 is a side elevation of the device shown in Fig. 3;

Fig. 5 is a detail taken on line 5—5 of Fig. 4 showing a latch device adapted to be controlled and actuated by spring pressure and electromagnets;

Fig. 6 is a perspective detail of guide blades for guiding the cards into separate pockets of the machine;

Fig. 7 is a detail of the electromagnets used to release and to actuate the sorting control device;

Fig. 8 is a view of the same electromagnets with parts in moved position;

Referring to the drawings the machine includes

a base or frame 1 mounted upon legs 2 and supporting 13 receiving pockets 3 separately numbered 1 to 9 and 0, 11, 12 and R. All of these designations are carried by the card as shown in Fig. 6 excepting the R. When the machine is set to sort the cards under control of a particular column a perforation in one of the 12 positions on the card will cause that card to be sorted into the corresponding pocket. A card having no perforation in the column controlling sorting will be fed to the R or reject pocket.

A plurality of guide blades 4 are mounted across the tops of the several pockets and serve to form paths to the separate pockets.

In Fig. 2 the right hand ends of the blades 70 terminate at 5. The left hand end of the lowermost blade is attached to and terminates at a block 6 above the first or 9 pocket. The left hand end of the next blade above the lowermost is attached to and terminates at a block 7 above the 76 8 pocket, etc. A card being fed from the stack 8 moves between upper and lower guide plates 9, 10. Normally all of the guide plates 4 are held above the plane of the oncoming card 8a so that unless they are lowered the card will pass under 80 all of the blades and drop into the 9 pocket. If the lowermost blade is lowered and all the other blades are held in their upper position the card will pass between the lowermost blade and the next one and will be guided across the 9 pocket 85 and dropped into the 8 pocket, etc.

If all the blades are lowered the card will pass above the uppermost one and below a strip or plate 11 which together form a path adapted to carry the card into the R pocket. The right 90 hand ends of the blades 4 may be slightly curved downwardly so that as all of the blades rest against the underside of the plate 11 at 11a they will tend to curve downwardly below the plane of the oncoming card so that the card will be 95 fed above all of the blades.

Associated with each blade is a cam disk 12 mounted on a shaft 13. A portion 12a of the disks may be concentric and the portion 12b may be eccentric. Each disk is provided with a drop or shoulder portion 12c so that as the shaft 13 turns counterclockwise its blade will be lowered from the upper or concentric periphery 12a to the lower or cam periphery 12b. The shoulders 12c are so adjusted on the shaft 13 that as the latter rotates the blades 4 will be dropped one after another until they have all been lowered below the plane of the card.

The ends 12d of all of the cam portions 12b may be in alignment so that at a definite time 110

after the last one of the blades has been dropped all of the blades will be simultaneously raised to their normal positions above the plane of the card. This position may be termed the zero point in the cycle of operation of the machine. This, then is also the point in the cycle shortly before the "9" position on the card which is about to be sensed reaches the sensing brush 14 and the card which has been sensed has already entered between the blades.

Card feed

The machine is driven by an electric motor 15 which is connected by a belt not shown here to the main driving shaft 16. This shaft is connected to the card feeding rollers 17 and also to a shaft 18 on which is fixed a cam 19 adapted to move an arm 20 against the action of springs 21. The arm is pivoted at 22 and is connected at its upper end to a plate 23 provided with a card picker 24. The cam 19 moves the picker toward the left and the spring 21 acting against the arm 20 moves the picker back toward the right. Each movement of the picker to the left causes the lowermost card in the stack to be moved forward into cooperation with the first set of feed rollers 17. These rollers then feed the card to the next set of rollers. As the card is being fed from the first to the second set of rollers, it passes under the electric sensing brush 14. The rollers continue to feed the card across the machine until it drops into one of the several sorting pockets.

Sensing brush

The brush 14 is mounted in an arm 25 carried on a threaded rod 26. This rod is provided with a crank arm 27 which when turned causes the arm 25 to be screwed to one side or the other. In this way the brush 14 may be adjusted to cooperate with any of the several columns of perforation positions on the card. The brush is thus adjusted to cooperate with the column upon which sorting is to be effected. As the card feeds under the sensing brush the latter will cooperate successively with the several hole positions beginning with "9" and running down through the several digit values through the zero position and the 11 and 12 positions. A shaft 13 which carries the cam disks 12 is also driven by the main shaft 16 and operates synchronously with the feeding of the card. In other words, each of the cam disks 12 corresponds with one of the 12 hole positions on the card. The "9" position passes under the sensing brush before any of the guide blades 4 has been dropped. If there is a perforation in the "9" position an electric circuit is closed and this in turn locks all of the guide blades in their upper position so that none of them will be dropped. Then, when the card reaches the ends of the blades at 5 it will pass under all of the blades and be guided into the first or "9" pocket. If there is no perforation in the "9" position but one in the "8" position one of the guide blades will be dropped just after the "9" position passes under the brush and then when the "8" position having a perforation, passes under the brush, the latter will reach through the perforation and engage the roller 28 to close the control circuit which then locks all of the guide blades thus preventing any others from dropping. Now when the card reaches the guide blades it will pass over the top of the lowermost blade and under the other blades and will be guided into the second or "8" pocket. Similarly, when the hole appears in any other

of the "12" positions in the column the brush will reach through closing the control circuit and causing the guide blades to be locked in the position that they then occupy and the card will be guided into the pocket corresponding to the position where the perforation appears.

Guide locking mechanism

Associated with each of the cam disks 12 is an arm 29 pivoted at 30 and pulled downwardly by a spring 31. This tends to hold the arm 29 in cooperation with its respective cam disk 12. Thus when the drop shoulder 12c moves from under the left hand end of the arm 29 the latter will drop upon the eccentric portion 12b of the disk. The end of each of the guide blades 4 rests upon one of the arms 29 so that as the arms drop the ends of the blades drop also. Each arm 29 is provided with a latch projection 32 which when in normal position is above and to the left of a latching plate 33 which reaches across and is adapted to cooperate with all of the projections 32. The latching plate 33 is pivoted at 34 on shaft 35 and continuing downwardly constitutes the armature of an electromagnet 36. The magnet 36 when energized will tend to rock latching plate 33 counterclockwise. A latch 38 is, however, provided to cooperate with the plate 33 as in Fig. 7 to hold the lower end thereof to the left so that the upper end will maintain the position shown in Fig. 2 with respect to the latching projections 32 on arms 29. The latch 38 rests near its right hand end on a knife edge 40 formed in the frame 41 and is pulled downwardly at its right hand end by a spring 42 connected to a binding post 43.

Shoulders 44 on latch 38 resting against the inner face of the frame 41 prevent the latch from sliding toward the right. This latch in turn constitutes the armature of a second electromagnet 36a. When the armature 33 is moved to the left from the position of Fig. 8 to that of Fig. 7, the latching armature 38 will snap into position as in Fig. 7 to hold the armature 33 in this position. A stop 45 is fixed on the armature 33 to limit the upward movement of the armature 38. A frame 46 pivoted at 47 is adapted to rest against the armature 33 and is actuated by a spring 48. The magnets 36 and 36a may be connected either in series or in parallel but preferably in parallel with the sensing brush 14 so that when the latter reaches through a perforation in the card and makes contact with the roller 28 an electric circuit will be closed through both of these magnets. The energization of magnet 36a causes depression of its armature 38 thus releasing the armature 33 so that the latter will be free to rock into latching position with respect to the projections 32 on the arms 29. The upper or latching portion of the armature 33 will then move under all of the projections 32 of those arms 29 that have not yet dropped and over the upper portion of projections 32 of those of the arms that have dropped. The armature 33 thus latches all of the arms 29 either in their dropped position or in their normal upper position. The parts will then be maintained in these relative positions as the card continues to move toward the ends of the guide blades and passes between those that have dropped and those that have not. The card will then be guided by the blades to that pocket which corresponds to the position of the perforation through which the brush 14 passed to energize the sorting magnets.

The magnet 36 serves to rock the latching armature 33 into latching position with respect to 150

the members 29. In addition to this a spring 48 acting through the frame 46 helps to move the armature 33 into latching position. The armature 33 may be made very light and having substantially frictionless bearing is adapted to respond very rapidly to the energization of magnets 36a. The armature 33 on the other hand which is slightly heavier due in part to the fact that it must cooperate with all of the arms 29 is actuated by a spring and also by the magnet 36. These forces thus serve to produce an extremely rapid operation of the armature so that the sorting machine operates at a very high speed. At the proper time in the card cycle of the machine the latching armature 33 is restored to its normal position by one or more cams 49 on the shaft 18. These cams cooperate with a bail 50 pivoted on the shaft 34 and adapted to be moved toward the right (Figs. 2 and 4) to engage the latching armature 33 to move the latter back to its normal position as in Fig. 2. This will release armature 33 and also rock the frame 46 counterclockwise. It will thus permit the armature latch 38 to be actuated by its spring 42 into the position of Fig. 7. It also causes frame 46 to positively raise the armature 33 to overcome possible residual magnetism. Springs 51 connected between the bail 50 and a bracket 52 hold the bail in cooperation with the cam or cams 49.

30. In operation the spring 48 presses very lightly against the member 33 but not with sufficient force to make it hard to depress the latching armature 33. When the magnets 36, 36a are simultaneously energized the magnet 36a acts quickly upon its armature depressing the latter to release the armature 33. It is necessary to effect a very rapid operation of an armature member 33. If a spring alone were relied upon for this purpose such spring would have to be of such strength that it would cause a retarding effect upon the depression of armature latch 38. It would then be necessary for the magnet 36a to build up substantially to its highest efficiency before the armature 33 would be depressed. By using a light spring 48, however, the armature 33 will be depressed before the magnet builds up to its highest point. At about the time the armature 33 is completely depressed and the armature 33 has been released magnet 36 will have attained its greatest power and will act to move its armature 33 much faster than its spring 48 could move it. With this arrangement then, it is possible for the magnet 36a to unlatch the armature member 33 much more rapidly than would be the case with other constructions. Also the magnet 36 acting with greater force than a spring, moves the armature 33 very rapidly. By restoring both armatures 33 and 38 positively I also attain greater speed of operation of the device. For instance, if springs are relied upon to restore the armatures 33, 38 to their normal positions such springs would have to overcome residual magnetism and this would retard the operation. It would become necessary to insert non-magnetic material between the core of the magnet and the armature to hold these parts slightly separate so as to reduce the effect of the residual. Where the parts are restored positively, however, it is possible to omit this intermediate or separating substance, and the armature may thus be set at a normal position much closer to the core of the magnet. The magnet thus exerts a far greater force and acts correspondingly faster upon the armature.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore to be limited only as indicated by the scope of the following claims.

I claim:

1. In a record card sorting machine, a plurality of receiving pockets, means for directing cards to said pockets, means for controlling said directing means including a pair of electromagnets one of said magnets being provided with an armature for controlling the directing means and the other of said magnets being provided with an armature adapted to latch the first named armature against action by its magnet, and record controlled means for simultaneously energizing both of said magnets.

2. In a perforated card controlled sorting machine, a plurality of card receiving pockets, guides for directing cards into said pockets, movable arms for controlling the positions of said guides, a latch for latching said arms in operative or inoperative positions, an electromagnet adapted to operate said latch and a second electromagnet provided with an armature adapted to normally hold said latch in inoperative position.

3. In a card sorting machine, a plurality of card sorting elements, a single latch for controlling said elements, a spring and electromagnet adapted to operate said latch for latching, means for normally holding the latch in inoperative position and a second electromagnet adapted to move said holding means to inoperative position to release said latching means.

4. In a card sorting machine, a plurality of card receiving pockets, a plurality of guides for guiding cards into said pockets, differential cams for controlling the positions of said guides, a latch for maintaining the guides in said position, an electromagnet for actuating said latch to operative position, a second electromagnet provided with an armature for normally holding said latch in inoperative position and a perforation sensing brush for closing a circuit through said electromagnets to effect the release and operation of the latching means.

5. In a record card controlled machine, means for feeding record cards, means for sensing perforations in a card being fed, means for controlling the operation of the machine including a movable member serving also as an electromagnet armature, an electromagnet adapted when energized to actuate said member, a latch for holding said member against actuation, a second electromagnet, said latch serving also as an armature of said second electromagnet and adapted when actuated thereby to release said member, said electromagnets being energized under control of said sensing means.

6. In a record controlled sorting machine, means for feeding records, sorting mechanism, a control device for controlling said sorting mechanism, resilient means tending to actuate said control device to operative position, means for locking said control device in inoperative position, electromagnetic means controlled by the records being sorted for moving said locking means to inoperative position and to aid said re-

- silient means in moving said device to operative position and means operating in synchronism with the feeding mechanism for restoring said device to inoperative positon.
- 5 7. In a sorting machine, distributing mechanism, a movable element for controlling operation of said mechanism, a latch for holding said element in normal position, and means for simultaneously applying force to said latch and said element to move the latch to releasing position and to move the element with increasing force to operative position.
